CLAIM

I claim the ornamental design for pants, as shown and described.

DESCRIPTION

FIG. 1 is a front perspective view of pants, showing my new design;

FIG. 2 is a left side view thereof;

FIG. 3 is a front view thereof; and,

FIG. 4 is a rear view thereof.

The broken lines depict features and portions of the pants that form no part of the claimed design.

1 Claim, 4 Drawing Sheets(56)
